(57) **CLAIM**

The ornamental design for a wind spinner, as shown and described.

DESCRIPTION

FIG. 1 is a front perspective view of a wind spinner, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlarged view of FIG. 5.

The broken-line circle, which illustrates the boundary of the enlarged view shown in FIGS. 5 and 9, and the broken-line lead line in FIG. 5, together represent a detail callout. The broken lines form no part of the claimed design.
